UNITED STATES PATENT OFFICE.

CHARLES J. WILEY, OF YORKTOWN, NEW YORK.

PRINTING-TELEGRAPH.

1,116,657.

Specification of Letters Patent. Patented Nov. 10, 1914.

Application filed June 16, 1913. Serial No. 773,838.

To all whom it may concern:

Be it known that I, CHARLES J. WILEY, a citizen of the United States, residing at Yorktown, in the county of Westchester and State of New York, have invented an Improvement in Printing-Telegraphs, of which the following is a specification.

My invention relates to a printing telegraph, and particularly to that class of these instruments commonly known as stock tickers. In the use of these instruments, as now generally employed, stock or other quotations are reported telegraphically by the instruments through a number of type wheels, 15 suitably actuated, and a tape, and in the most common form of the instrument, a pair of type wheels are employed, one being used for printing the names of the stocks and the other for printing the quotations, the names 20 necessarily being printed on one line and the quotations on another. Oftentimes, in a busy market, the operator has difficulty in quoting stocks with sufficient rapidity, and the purpose of my present invention is to increase the facilities of reporting stock 25 quotations and those of other commodities by using a plurality of independently operated telegraphic instruments, some of which may be used for printing the quotations of the 30 more active stocks and others for printing the quotations of the less active stocks, all of the quotations being printed by the various machines, in accordance with my invention, upon a single tape.

As illustrated in the drawing, I prefer to employ two printing instruments, one placed in advance of the other, and through the printing and tape feeding devices of each a suitable tape is passed in such a manner as 40 to leave sufficient tape between the printing wheels and feeding devices of each instrument to be used independently of one another.

The novelty of my present invention relates 45 in the application of a single tape or ribbon to two or more independently operated printing telegraph machines, and so controlling the tape supply as to make it possible to operate these printing telegraph 50 instruments independently of one another.

It is also part of my invention to so connect the instruments in line with suitable transmitters that either printing instrument may be used separately, and when so used the 55 tape feed is uniform through all the printing

instruments, all of which will be hereinafter more particularly described.

In the drawing, Figure 1 is a side elevation, more or less diagrammatic, illustrating a pair of printing telegraph instruments embodying my present invention. Fig. 2 is a diagrammatic plan of the transmitting instruments. Fig. 3 is a diagrammatic plan of the parts shown in Fig. 1. Fig. 4 is an enlarged cross section on line *x-x* Fig. 1. Fig. 5 is a cross section on line *y-y*, Fig. 1, showing in plan the sector employed for striking the tape between the instruments to maintain the proper sag therein, and Fig. 6 is a sectional elevation on the line 6-6 of Fig. 4.

Referring to the drawing, and particularly to Fig. 1, I prefer to employ a pair of printing telegraph instruments A, B, which, as indicated in this figure, are mounted in a common frame 11, although manifestly these instruments may be mounted in frames of their own, each independent of the other. These instruments, as is common in apparatus of this kind, include type wheels, indicated at 12 in the instrument A, and 13 in the instrument B. In the instrument A there are magnets 14 adapted to operate an escape lever 15, to rotate the type wheel 12, and in the instrument B there are similar magnets 16 adapted to operate an escape lever 17 for controlling the type wheel 13, the type wheel 12 of the instrument A being actuated through a suitable train of gears 18, by means of a weight 19 or otherwise, and the type wheel 13 of the instrument B being similarly actuated through a train of gears 20 and suitable weight 21 or otherwise.

In the instrument A is the usual printing magnet 22, the armature of which operates a printing lever 23, normally maintained in its initial position by a spring 24 and carrying at its free end the tape wheels 25 and suitable mechanism for feeding the tape. Also in the instrument B is a printing magnet 26 and a printing lever 27, which is normally maintained in its initial position by a spring 28. At its free end the printing lever 27 carries the tape rolls 29 and suitable mechanism for feeding the tape each time the printing lever is operated.

Suitably fixed in the frame 11 is a shaft upon which a reel 30 is mounted, and from the reel 30 the tape 31 is fed to and through

the tape wheels 29 of the instrument B and the tape wheels 25 of the instrument A. Suitably mounted in the frame 11 is a magnet 32. This magnet is in the main line 34 with the printing magnet 22 and the type wheel controlling magnets 14 of the instrument A. Also suitably mounted on the frame 11 is a magnet 33, and this magnet is in the main line 35 with the printing magnet 26 and the type wheel controlling magnets 16 of the instrument B. The armature 36 of the magnet 33 is connected to a lever 37, which, at one end, as indicated at 38, is pivoted to the frame 11, and this lever 37 is normally maintained in its initial position by means of a spring 39 or otherwise.

Suitably mounted in the frame 11 is an arbor 40, and on this arbor 40 is fixed a pinion 41 and a ratchet wheel 42. Between the pinion 41 and the ratchet wheel 42 and loosely mounted on the arbor 40, is a bell crank lever, one arm of which is indicated at 43 and the other at 44. Pivoted connected, adjacent to the free end of the arm 43 of this bell crank lever, is a pawl 45 adapted to engage the teeth of the ratchet wheel 42 and normally maintained in engagement therewith by the spring 46. The free end of the arm 44 of the bell crank lever of the arbor 40 is connected to the lever 37 by a link 47. 48 designates a pawl which is suitably connected to the frame 11 and adapted to engage the teeth of the ratchet wheel 42 to prevent the turning thereof in a counter-clockwise direction, as seen in Fig. 1. I also employ a bar, indicated at 49, the upper end of which is preferably circular in cross section and is indicated at 50. Between the body of the bar 49 and its upper circular end is a shoulder 51. The circular end 50 of the bar 49 passes through an opening provided therefor in the head 52, which, on the opposite side, is provided with a cylindrical projection 53 adapted to span a circular lug 54, suitably secured to the frame 11. Passing through the projection 53 are screws 55, which extend into recesses 56 provided therefor in the surface of the lug 54.

In its outer face, adjacent to the lower end, the bar 49 is provided with a longitudinal slot 57, which is adapted to receive a pin 58 carried by one end of the arm 59 of a bell crank lever which is pivoted in the frame 11 at the pivotal point 60. The other arm 61 of this bell crank lever carries the armature 62 of the magnet 32, and the armature 62 with the bell crank lever is maintained in a normal position against an adjustable stop screw 64 by means of a spring 63. Along one edge of the bar 49 is a ratchet 66, adapted to engage the teeth of the pinion 41, and extending between the upper surface of the shoulder 51 and the lower surface

of the head 52, and surrounding the end 50 of the bar 49, is a spring 65, the function of which is to exert a downward pressure against the bar 49. The bar 49 carries a sector 99, and these parts are so placed that when the bar 49 is released from the pinion 41 and forced downwardly by the spring 65, the lower surface of this sector 99 strikes that portion of the tape between the type wheels of the printing instruments and forces the same downwardly to provide for the necessary sag between the tape feed devices of the instruments to permit the instruments to be operated independently of one another.

The magnet 33 is so wound as to operate under the same conditions that the magnet 26 operates, so that each time the magnet 26 is operated to print a character on the type wheel 13 of the instrument B, the armature 36 is attracted to the core of the magnet 33, moving downwardly the lever 37, the link 47 and the arm 44, and moving the arm 43 from left to right and turning the ratchet wheel 42 a predetermined distance. This partial revolution of the ratchet wheel imparts a similar partial revolution of the pinion 41, and this in turn, through the rack 66, raises the bar 49, compressing the spring 65, and this operation will be repeated each time the character is printed by the instrument B until the rod 49 is in its uppermost position, when the pin 58 will be at the lower end of the slot 57.

The magnet 32 in the main line 34 of the instrument A is so wound that it will not operate, that is to say, become energized by the same current which energizes the printing magnet 22 of the instrument A, and this magnet 32 is under the control of the operator, in order that a current of sufficient strength may be sent through the same to energize it, so as to attract the armature 62 against the action of the spring 63. This moves the arm 59 from right to left, as shown in Fig. 1, and causes the pin 58 to swing the lower end of the bar 49 sufficiently far to cause the rack 66 to be disengaged from the teeth of the pinion 41, the head 52 of the bar 49, it will be understood, swinging on the lug 54. When the rack is freed from the teeth of the pinion 41, the spring 65 is brought into play, causing the bar 49 to descend rapidly, permitting the sector to strike the tape between the printing wheels of the instrument and to carry the same downwardly a predetermined distance. In this action, the tape in the instrument A will be locked in position against the type wheel, the magnet 22 having been energized to operate the printing lever 23 by the same current which energizes the magnet 32, so that when the sector 99 strikes the tape and carries the same downwardly between the printing instrument, the tape will be un-

wound from the reel 30 and passed through the feed rolls of the instrument B, and this may be done during a pause in the printing operation of the instrument B or at other times so as not to interfere with its work, and may be done sufficiently often to cause the necessary sag in the tape between the instruments to provide for a proper feed of the tape for the printing instrument A. In some instances, for example, where the instrument B is used to a greater extent than the instrument A, the sag of the tape between the instruments may become excessive, and this is taken care of by the operator controlling the transmitter to the instrument A, merely repeating a sufficient number of times to take up the excessive sag in the tape.

If through any means the sag in the tape becomes insufficient for the requirements of instrument A, a similar operation of the transmitter of instrument B will replenish it. During both of these operations the instruments should be at unison or rest.

Referring to Fig. 2, I have shown diagrammatically at C and D suitable transmitting instruments for operating the printing instruments A and B respectively. Each of these transmitting instruments preferably comprise an operating key 67, a toothed wheel 68 turned thereby, and spring actuated levers 69, for reversing the current over lines 34 and 35, the pivotal points of the levers 69 forming the terminals to which connections are made to a battery 70. Each transmitter is provided with line terminals, indicated at 71 and 72 in transmitter C, and 73 and 74 in transmitter D. The other features of these transmitting instruments are old and their operation obvious from the drawing, and for this reason no further description of them will be made.

In order to enable either of the printing instruments to be used independently of the other and at the same time to provide for a uniform tape feed, when either instrument is used alone, I prefer to employ, in conjunction with transmitter C, a contact 75 and a switch 76, by means of which the circuit is closed through the contact 75, the contact 75 being connected to the line terminal 71 of the transmitter C by a wire 77. Similarly in connection with the transmitter D, I employ a contact 78 and a switch 79, the contact 78 being connected to the line terminal 73 of the transmitter D by the wire 80. Also associated with the transmitter C, I employ a magnet 81, and in connection with the transmitter D a similar magnet 82. One terminal of the magnet 82 is connected by a wire 83, with the line terminal 72 of the transmitter C, the other terminal of the magnet 82 being connected by the main line wire 34 to the printing instrument A. One terminal of the magnet 81 is connected to

the line terminal 74 of the transmitter D by a wire 84, and the other terminal of the magnet 81 is connected to the main line 35 to the printing instrument B. Associated with the magnet 81 is an armature 86 carried by a lever 85, pivotally mounted to permit the armature 86 to be attracted to the core of the magnet and to be normally maintained in an open position by a spring 87.

The lever 85 is connected to the line or wire 77 by means of a wire 88. 89 designates a contact adapted with the switch 76 to close the circuit through the line 34 when the switch is moved to the position shown in the dotted lines in Fig. 2. Suitably mounted in the contact 89 is a contact screw 90, which, together with the contact screw 91, limits and determines the extent of the movement of the lever 85. Similarly in connection with the magnet 82, I employ a lever 92 carrying an armature 93 adapted to be attracted to the core of the magnet 82 and maintained in its normal position by means of a spring 94. The lever 92 is connected to the line or wire 80 by a wire 95. 96 designates a contact, which, with the switch 79, when moved to the right as shown in Fig. 2, is adapted to close a circuit to the main line 35.

Suitably connected to the contact 96 is a contact screw 97, which, together with a contact screw 98, regulates and determines the movement of the lever 92. The full line positions of the switches 76 and 79, as indicated in Fig. 2, are the open positions thereof, and when the printing instruments are to be employed together, that is, simultaneously or independently of one another, it is necessary to move these switches into contact respectively with the contacts 75 and 78, when, as will be understood, no function is performed by the magnets 81 and 82.

When it is desired, however, to operate either printing instrument without using the other, as for example, should it be desired to operate printing instrument A and to cut out printing instrument B, the switch 79 is moved into contact with the contact plate 96, and the switch 76 moved into contact with the contact plate 75.

As hereinbefore stated, when the instruments are arranged to be operated independently and also simultaneously, the switch 79 is against the contact 78, and the switch 76 is against the contact 75. When the switches are in these positions, the instrument A will be operated by the transmitter C, and the instrument B operated by the transmitter D.

The circuits included in the operation of the instrument A are:—From one terminal 71 of the transmitter C, through the transmitter 115 to the opposite terminal thereof, including the battery 70, through the line 83, magnet 82, the line 34, the magnet 14, the magnet 22, the magnet 32, thence through the other end of the line 34 to the switch 76, the con-

90 95 100 105 110 115 120 125 130

96 97 98 99 100 105 110 115 120 125 130

100 105 110 115 120 125 130

100 105 110 115 120 125 130

tact 75, the line 77, thence to the terminal 71, or the point of beginning. Simultaneously, the circuits employed in operating the instrument B are as follows:—From one terminal 73 on the transmitter D, through the transmitter, including the battery 70 to the other terminal 74 thereof, through the line 84 to the magnet 81, through one side of the line 35 to the magnet 33, thence to the other side of the line 35 to the switch 79, the contact 78, the line 80, to the terminal 73 or the point of beginning. Inasmuch as these several circuits are independent for the separate instruments, it will be apparent that both transmitters may be operated simultaneously, which will cause the simultaneous operation of the respective instruments. In operating the instruments together, each time the instrument B is actuated, the magnet 33 is energized, which causes a step-by-step elevation to be imparted to the rod 49 until it has reached its maximum height, and when it becomes necessary to cause a sag in the tape, provided the instrument A is operated faster than the instrument B, the operator closes a circuit, thereby energizing the magnet 32, releasing the bar 49, permitting the same to drop so that the sector 99 contacts with and depresses the tape, causing the desired sag therein. It will also be understood that in the event of the instrument B being operated faster than the instrument A, it will be necessary to feed or pull the tape, as required, through the tape feeding mechanism of the instrument A. It will be further understood that the several magnets hereinbefore described are actuated by direct current impulses of both polarities.

In operating the printing instrument A by the transmitter C, the switch 76 having been moved into contact with the contact plate 75, and the switch 79 moved into contact with the contact plate 96, each time a sufficient pause is made in the transmitter C to operate the printing instrument A, the current in the main line 34, which also includes the magnet 82, will energize this magnet, attracting the armature 93 to its core, thereby moving the lever 92 from contact with the screw 98 to contact with the screw 97, so as to close the circuit, through the transmitter D, the wire 95, the lever 92, the contact plate 96, the switch 79 to the main line 35 to the magnets in the printing instrument B, energizing the same and causing the printing magnet 26 to operate the printing lever 27, which, as will be understood, actuates the tape feed so that each time the tape is fed by the printing instrument A, it is also fed a corresponding distance by the printing instrument B, hence a uniform sag in the tape is maintained between the instruments and in so operating the apparatus the printing wheel of the instrument B

is turned to a blank position and suitably held therein so that when this printing lever is actuated, no impression will be made on the tape.

Obviously, to operate the printing instrument B, cutting out the printing instrument A, it would be necessary to reverse the positions of the switches 76 and 79, that is to say, the switch 76, to accomplish this purpose, would have to be moved into contact with the contact plate 89 and the switch 79 with the contact plate 78.

The current of greater than normal strength necessary to energize the magnet 32 may be obtained from a battery 100, or other source of electrical energy, in a line 101, connected across the main lines 34, as shown in Fig. 2. In this line 101, there is also a switch 102 which is normally open but which is closed when necessary to energize the magnet 32 to operate the devices as hereinbefore described for causing a desired sag in the tape.

I claim as my invention:

1. In a printing telegraph, a plurality of independently operated printing instruments, a single tape common to all the said instruments, and means for maintaining a predetermined slack in the tape lengthwise thereof between adjacent instruments.

2. In a printing telegraph, a plurality of printing instruments, a single tape common to all the said instruments, a transmitter for each printing instrument, and means associated with the printing instruments for maintaining a predetermined slack in the tape lengthwise thereof between adjacent instruments.

3. In a printing telegraph, a plurality of independently operated printing instruments, a tape common to all the said instruments, means for maintaining a predetermined slack in the tape lengthwise thereof between adjacent instruments, and means whereby when any of the printing instruments is cut out the tape is fed uniformly through all the printing instruments.

4. In a printing telegraph, a pair of independently operated printing instruments, a single tape common to both printing instruments, and means for maintaining a predetermined slack in the tape lengthwise thereof between the said instruments.

5. In a printing telegraph, a pair of printing instruments, a single tape common to both printing instruments, a transmitter for each instrument, and means for maintaining a predetermined slack in the tape lengthwise thereof between the said printing instruments.

6. In a printing telegraph, a pair of independently operated printing instruments, a tape common to both the printing instruments, means for maintaining a predetermined slack in the tape lengthwise thereof

between the said printing instruments, and means whereby when one of the printing instruments is cut out, the tape is fed uniformly through both the instruments.

5 7. In a printing telegraph, a frame, a front and a rear printing instrument mounted in the said frame, a tape common to both the said front and rear printing instruments, and means for maintaining a predetermined slack in the tape lengthwise there-
10 of between the said instruments.

8. In a printing telegraph, a frame, a front and rear printing instrument mounted in the said frame, a tape common to both the said instruments, a magnet in the line leading to the front printing instrument, and devices actuated by the said magnet to contact with the said tape to maintain a predetermined sag lengthwise of the tape be-
15 tween the front and rear printing instru-
20 ments.

9. In a printing telegraph, a frame, a front and rear printing instrument mounted in the said frame, a tape common to both the said front and rear printing instruments, a rod, a device carried by the rod and adapted to contact with the said tape to maintain a predetermined sag therein be-
25 tween the front and rear printing instru-
30 ments, means in the line leading to the rear printing instrument for elevating the said rod, a magnet in the line of the front printing instrument and devices actuated by the said magnet in the line to the front print-
35 ing instrument for releasing the said rod.

10. In a printing telegraph, a frame, a front and a rear printing instrument mounted in the said frame, a tape common to both of said printing instruments, a rod, a device carried thereby adapted to contact with the tape to cause a predetermined sag in the same between the printing instruments, means controlled by the current in the line to the rear printing instrument for raising
40 the said rod with a step-by-step movement each time the said rear printing instrument is operated, and means controlled by the current in the line to the front printing instrument for releasing the said rod and per-
45 mitting it to drop and strike the tape.

11. In a printing telegraph, a frame, a front and a rear printing instrument mounted in the said frame, a tape common to both of said printing instruments, a rod, a device carried thereby adapted to contact with the tape to cause a predetermined sag in the same between the printing instruments, means controlled by the current in the line to the rear printing instrument for raising
50 the said rod with a step-by-step movement each time the said rear printing instrument is operated, means controlled by the current in the line to the front printing instrument for releasing the said rod, and means opera-
55 tive when the rod is so released for causing

the same to descend rapidly to cause the said device carried thereby to strike the tape.

12. In a printing telegraph, a frame, a front and rear printing instrument mounted in the frame, a tape common to both the said instruments, a rod, a device carried thereby adapted to contact with the tape to maintain a predetermined slack in the same between the said instruments, an arbor mounted in the frame, a ratchet wheel on the said arbor, a pawl operating on said ratchet wheel, a magnet in the line to the said rear printing instrument, devices operated by the said magnet for actuating the said ratchet with a step-by-step movement, 70 devices for connecting the said arbor and the said rod to raise the rod with a corresponding step-by-step movement, and devices controlled by the current in the line to the said front printing instrument for re-
80 leasing the said rod from its elevating de-
85 vices and permitting the same to drop to cause the device carried thereby to strike the tape between the printing instruments.

13. In a printing telegraph, a frame, a front and rear printing instrument mounted in the frame, a tape common to both the said instruments, a rod, a device carried thereby adapted to contact with the tape to maintain a predetermined slack in the same between the said instruments, an arbor mounted in the frame, a ratchet wheel on the said arbor, a pawl operating on said ratchet wheel, a magnet in the line to the said rear printing instrument, devices operated by the said magnet for actuating the said ratchet with a step-by-step movement, 90 a pinion also mounted on the said arbor, a rack on one side of the said rod, with which the teeth of the said pinion are normally ad-
95 pted to engage, in order that the step-
100 by-step movement imparted to the arbor by the said ratchet and pawl is transmitted to the rod through the pinion and rack to raise the rod, and devices controlled by the current in the line to the front printing instrument for moving the said rack away from the said pinion to permit the rod to drop, causing the device carried by the rod 105 to contact with the tape.

14. In a printing telegraph, a frame, a front and rear printing instrument mounted in the frame, a tape common to both the said instruments, a rod, a device carried thereby adapted to contact with the tape to maintain a predetermined slack in the same between the said instruments, an arbor mounted in the frame, a ratchet wheel on the said arbor, a pawl operating on said ratchet wheel, a magnet in the line to the said rear printing instrument, devices operated by the said magnet for actuating the said ratchet with a step-by-step movement, 110 a pinion also mounted on the said arbor, a rack on one side of the said rod, with which 115

the teeth of the said pinion are normally adapted to engage, in order that the step-by-step movement imparted to the arbor by the said ratchet and pawl is transmitted to the rod through the pinion and rack to raise the rod, a magnet in the line to the said front printing instrument, and a device controlled by the said magnet for maintaining the said rack in contact with the teeth of the said pinion and for removing the rack from contact with the teeth of the pinion to permit the rod to drop so as to cause the device carried thereby to strike the tape between the printing instruments.

- 15 15. In a printing telegraph, a frame, a front and rear printing instrument mounted in the frame, a tape common to both the said instruments, a rod mounted at one end to swing and provide in one side adjacent its free end with a longitudinal slot, a device carried by said rod and adapted to contact with the tape to maintain a predetermined slack in the same between the said instruments, an arbor mounted in the frame, a ratchet wheel on the said arbor, a pawl operating on said ratchet wheel, a magnet in the line to the said rear printing instrument, devices operated by the said magnet

for actuating the said ratchet with a step-by-step movement, a pinion also mounted on the said arbor, a rack on one side of the said rod, with which the teeth of the said pinion are normally adapted to engage, in order that the step-by-step movement imparted to the arbor by the said ratchet and pawl is transmitted to the rod through the pinion and rack to raise the rod, a magnet in the line to the said front printing instrument, a bell crank lever mounted in the said frame, an armature for the last aforesaid magnet carried by one arm in the said bell crank lever, a pin secured to the other arm of the said bell crank lever and passing within the said longitudinal slot in the said rod, means for maintaining the said bell crank lever in a normal position in which the said rack is in engagement with the teeth of the said pinion, and means operative when the rack is released from the pinion to cause the rod to rescind rapidly and a device carried thereby to strike the tape.

Signed by me this 2nd day of June, 1913.
